UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A FIREPLACE-FRONT.

SPECIFICATION forming part of Design No. 36,059, dated September 9, 1902.

Application filed July 29, 1902. Serial No. 117,578. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Fronts, of which the following is a full, clear, and exact description, reference being had to the accompanying drawing, forming part hereof, in which the invention is illustrated in front view.

The leading features of the design consist in a frame the sides of which are constituted of panels bearing in relief the representations of fluted columns. The cross-piece is in the shape of a hood inclosed in a molding and having the representation of a shield at its center, with foliation extending therefrom. At the corners of the frame, above the tops 20 of the columns, are spikes holding wreaths

from which streamers extend inwardly. The center or summer front bears the representation of a forest scene on the banks of a stream of water, with the figures of two Indians sitting in front of a tepee spread in a cluster of 25 trees and the body of a deer depending from a branch of one of the trees. In the lower left-hand corner of the scene the prow of a canoe is shown drawn up on the banks of the stream.

30

I claim—

The ornamental design for a fireplace-front as herein described and shown.

In testimony whereof I have hereunto set my hand in the presence of two subscribing 35 witnesses.

THOMAS M. DUDGEON.
